UNITED STATES PATENT OFFICE.

CHARLES H. HOWLAND-SHERMAN, OF WASHINGTON, DISTRICT OF COLUMBIA,
ASSIGNOR TO THE HOWLAND-SHERMAN MANUFACTURING COMPANY, OF
WILMINGTON, DELAWARE, AND BALTIMORE, MARYLAND, A CORPORA-
TION OF DELAWARE.

COLUMN CAPITAL AND ATTACHMENT.

SPECIFICATION forming part of Letters Patent No. 712,299, dated October 28, 1902.

Application filed December 24, 1901. Serial No. 87,118. (No model.)

To all whom it may concern:

Be it known that I, CHARLES H. HOWLAND-SHERMAN, a citizen of the United States, residing at Washington, in the District of Columbia, have invented new and useful Improvements in Column Capitals and Attachments, of which the following is a specification.

My invention relates to improvements in columns for supporting floor-girders and other beams used in building construction of various kinds.

The object of the invention is to so construct the capitals of built-up iron or steel columns that their several detail parts, consisting of the top angle-plates, butt angle-plates, and gusset or side angle-plates, form what may be called a "cell," into or through which is placed a floor-girder, secured directly or indirectly to the capital by means of rivets, bolts, or other secure fastenings, and a transverse beam above the floor-girder, secured to the upward extension of said gussets.

Referring to the drawings, Figure 1 is an elevation of a part of a column with capital attached, showing in section a girder supported thereby and a cross-beam resting on said girder and riveted to the capital. Fig. 2 is a similar view with the girder and cross-beam omitted. Fig. 3 is a vertical section on the line 3 3 of Fig. 1. Fig. 4 is a horizontal section on the line 4 4 of Fig. 2. Figs. 5, 6, and 7 show in detail the several different parts which make up the capital.

Similar reference characters indicate similar parts in the several figures.

The column 82, as represented in Figs. 1, 2, and 3, is built up of the channel-beams 108 109 and an I-beam 110, placed centrally between them. The webs of the channel-beams are riveted to the flanges of the I-beam to form the structure shown in Fig. 3. To the column 82 is secured the capital, of which essential parts are the butt-angles 83 85, attached by rivets 84 to the web of the column channel-beams and supporting the floor-girders 86 directly upon their upper flanges, which flanges are riveted to the floor-girder 86. The gussets or side angles 87 88 are secured by rivets 89 to the flanges of the column channel-beams 108 109 in such manner as to inclose between them the floor-girder 86. The

gussets stand in a vertical position, one flange of each gusset extending above the upper plate of the floor-girder and being provided with holes for riveting the transverse beam to the gussets. The top angles 90 91, as indicated in Figs. 1, 2, and 3, are secured by through-rivets 92 to the top web-plate 93 of the floor-girder. The floor-girder, as shown, is a rectangular box-girder, its side channels 96 97 being secured to the top and bottom plates 93 95 by rivets 98 in the usual manner.

Having thus described my invention, I claim—

1. Duplex lateral gussets having flanges adapted to secure the floor-girders, and having base attachment to the sides of the capitals of columns to form an integral continuation of said capitals, substantially as set forth. 65

2. Duplex lateral gussets having flanges adapted to secure the floor-girders, and having base attachment to the sides of a capital of a column, said duplex lateral gussets adapted to form an embracing or semicircular capital for the column, substantially as set forth. 70

3. The combination, in a column-capital, of front and rear top or butt angles, lateral superiorly-flanged angular gussets, top angles, and suitable means for connecting said butt-angles and gussets to the column in such manner as to form an embracing or semicircular capital adapted to inferiorly support and laterally embrace a floor-girder, substantially as set forth. 85

4. Combined in a column-capital front and rear longitudinal butt-angles at the top, paired duplex lateral angular gussets secured at the sides to the top, and having vertical flanges at their tops, and top angles, the construction being such that it forms a semicircular or embracing capital, adapted to embrace laterally a longitudinal floor-girder resting on top of the column and to engage, by means of the superior flanges of said gussets, a transverse girder running crosswise of said longitudinal girder, substantially as set forth. 90

In testimony whereof I affix my signature in presence of two witnesses.

CHARLES H. HOWLAND-SHERMAN.
